United States Patent Office.

H. A. HARRIS, OF CENTER, TEXAS.

Letters Patent No. 99,889, dated February 15, 1870.

IMPROVEMENT IN SAW-SET.

The Schedule referred to in these Letters Patent and making part of the same.

To all whom it may concern:

Be it known that I, H. A. HARRIS, of Center, in the county of Shelby, and State of Texas, have invented a new and improved Saw-Set; and I do hereby declare that the following is a full, clear, and exact description thereof, which will enable others skilled in the art to make and use the same, reference being had to the accompanying drawings forming part of this specification.

Figure 1 represents a side view of my improved saw-set.

Figure 2 is an edge view of the same.

Figure 3 is a top view of the stem.

Similar letters of reference indicate corresponding parts.

This invention relates to a new implement which can be used for setting the teeth of all kinds of saws by hand, and without requiring any intricate machinery.

The invention consists in the arrangement of a perforated stem, which is to receive the teeth of the saw successively, and in the combination therewith of an L-shaped gauge, which regulates the degree of set.

A, in the drawing, represents a metallic bar or plate, of suitable size, and held in a handle, B.

It has near its upper end a suitable number of transverse apertures, d, one above the other, and all of different lengths, as shown in fig. 2. They are made higher at one side than at the other, as shown.

C is an L-shaped plate, fitted with its long perforated shank, a, through a mortise formed in the lower part of the bar A, and pivoted to such bar by a pin, c. Its other arm, e, projects upward on that side of A on which the apertures d are narrowest.

The bar A may have steps f formed on it, in line

with the lower sides of the larger apertures, and scales may be marked on such steps.

Along the mortise may also be marked a scale, b, to regulate the position of the gauge C, the said gauge being clamped in any desired position by a suitable set-screw, g.

The operation is as follows:

The saw being clamped in a suitable machine, the instrument is applied by fitting one tooth of the saw into one of the apertures d, as far as may be required. The instrument is then swung to bend the tooth until the end of the arm e strikes the blade. Then the device is applied to the second next tooth, and so forth, until all alternate teeth are bent in one direction. The instrument is then applied from the other side to the remaining teeth.

The various apertures d are of different sizes, to be adapted to the different kinds of teeth, and are made with inclined upper faces to prevent the straining of the edges of the teeth.

The gauge has numbers of apertures, and can also be clamped in any position to regulate the degree of set.

Having thus described my invention,

I claim as new, and desire to secure by Letters Patent—

A saw-set, consisting of the perforated bar A and of the L-shaped gauge C, adjustable by means of a set-screw, G, all combined and operating substantially as herein shown and described.

H. A. HARRIS.
